UNITED STATES PATENT OFFICE.

MYRTLE A. ANDES, OF HUNTINGTON, WEST VIRGINIA.

MUSIC-ROLL RECEPTACLE.

Application filed March 28, 1924. Serial No. 702,650.

To all whom it may concern:

Be it known that I, MYRTLE A. ANDES, a citizen of the United States, residing at Huntington, in the county of Cabell and State of West Virginia, have invented certain new and useful Improvements in a Music-Roll Receptacle, of which the following is a specification.

This invention relates to new and useful improvements in receptacles which are principally adapted for receiving music rolls which are played in player pianos.

One of the important objects of the present invention is to provide a music roll receptacle or box which is of such construction as to permit the music roll contained therein to be placed in the player piano together with the box thus obviating the necessity of having to remove the music roll from the box whenever it is desired to play the piece and thereby prevent any possibility of confusion in placing the music roll after it has been played in the wrong box.

A further object of the invention is to provide a music roll box of the above mentioned character, which is of such a construction as to permit the music roll to be played with the music box in position in the piano without interfering with the proper operation of the playing of the music roll, means being associated with the box for facilitating the opening of the same in order to permit the music roll to be attached to the winding roller on the player piano, means being further provided for holding the box in a stationary position when the same is disposed within the player piano.

A further object of the invention is to provide a music roll box which is simple in construction, inexpensive, strong and durable and furthermore adapted for the purposes for which it is designated.

Other objects and advantages of this invention will become apparent during the course of the following description.

In the accompanying drawing forming a part of the specification and in which like numerals designate like parts throughout the same,

Figure 1 is an end elevation showing the music box in position in a player piano with the sheet of roll music attached to the winding roller of the piano,

Figure 2 is a longitudinal sectional view of the music roll receptacle showing the

manner in which the music roll is supported therein,

Figure 3 is a transverse section through the device,

Figure 4 is a fragmentary plan view of 60 one end of the box with the cover removed,

Figure 5 is a transverse section through a modification, and

Figure 6 is a fragmentary side elevation 65 of the modification.

In the drawing wherein for the purpose of illustration is shown the preferred embodiment of my invention, the numeral 1 designates generally my improved music roll box and the same comprises the bottom section 2. Extending upwardly from the ends thereof are the end walls 3 and 4 respectively. Extending upwardly from the forward edge of the bottom section 2 is the lower portion of the front wall 5, the same 70 extending for the full length of the bottom section between the end walls 3 and 4. The rear longitudinal edge of the bottom 2 is provided with an upstanding portion 6 and hingedly secured thereto at its lower edge is 80 the rear wall 7.

The upper edge of the rear wall 7 extends substantially flush with the upper edges of the end walls and the rear wall is adapted to fit against the side flanges formed on each 85 of the end walls. Hinged to the upper edge of the rear wall 7 and adapted to extend over the flanges such as is shown at 8 formed on the top of the end walls is the top 9. The forward longitudinal edge of the top 9 extends substantially flush with the front face of the box and hinged thereto is the front section 10. The lower portion of the front section 10 is adapted to overlap the upwardly extending portion 5 whereby a front 95 wall is formed and any suitable fastening means such as is shown at 11 is provided for securing the upper section 10 to the lower section 5. When the parts are arranged as shown in Figure 3 of the drawing, a complete box substantially rectangular in cross 100 section is formed.

The box is preferably formed of paper, although it is to be understood that any any other suitable material may be substituted therefor, and I do not wish to limit myself to the particular kind of material to be used. The hinges which connect the various sections together may be in the form of cloth strips such as is illustrated at 12 although 105 110

any other suitable hinge construction may be provided for accomplishing the purposes and objects of the invention.

The flanges which are formed on the upper portions of the end walls and the construction of which is more clearly illustrated by the numeral 8 in Figure 4 of the drawing are provided with a cut out portion such as is shown at 13 to permit the insertion into 10 the receptacle or box of the music roll designated generally by the letter A. The trunnions B of the music roll will pass through the cut out portion 13 and will be adapted to be supported in the opening 14 provided 15 in the end walls whereby the trunnions may be engaged by the supporting pins provided in the player piano C in the manner well known in the art.

Heretofore when it has been desired to 20 play a music roll in the player piano, the music roll was first removed from its receptacle and inserted in the player piano in the manner well known in the art. After the music roll has been played, through carelessness of the player, the music roll is misplaced and is often put back in the wrong box. To prevent the placing of the music roll in the wrong box after the same has 25 been played, and to insure the proper music roll which is to be played to be removed from the box I provide a construction as above set forth which will be such as to permit the same to be inserted into the player piano together with the music roll, thus obviating the necessity of having to remove the music roll from the box in order to play the same.

Ordinarily a music roll is supported in the box 1 in the manner shown in Figure 3 of the drawing and suitable indicia is printed on the box so as to correspond with the piece of music which is on the sheet roll contained in the box. When it is desired to play the music roll, the box 1 together with the music roll therein is placed in the opening in the player piano in the manner as shown in Figure 1 of the drawing wherein the front wall 10 is folded back upon the rear of the top wall 9 and the latter is folded back upon the rear wall 7 and all the walls are then folded back under the bottom section 2, thus leaving the front, top and rear of the box open and permitting the sheet of music to be attached to the winding roller D in the usual manner. The sheet of music adapted to extend over the upper edge of the upwardly extending portion 5 in the manner as clearly illustrated in Figure 1.

For the purpose of holding the box 1 in the stationary position within the opening in the player piano, I provide a pair of arms on the upper flanges 8 of the end walls such as is shown at 15, each arm is pivoted at 16 and is adapted to swing outwardly into engagement with the adjacent side of the open-

ing in the player piano. If desired, a rubber cushion 17 may be placed on the outer free end of each arm providing the same is formed of metal so as to prevent the possibility of any injury to the piano. When not 70 in use, the arms are swung into the position as shown in Figure 4 of the drawing so as to permit the box to be readily closed.

After the roll of music has been played, the same may be rewound in the manner well known in the art and after the sheet has been detached from the winding roller, the box is then removed from the player piano and the parts are again assembled into the position as shown in Figure 3 and the front 75 upper section 10 is locked into engagement with the lower portion 5, thereby forming a complete enclosure for the music roll and thus permitting the music roll to be placed back into the music stand or the like for 80 future use. In this way there will be no possibility of confusing the music rolls with the wrong boxes and the handling of the music roll will be eliminated, thus preventing the tearing of the music roll as well as 85 the twisting of the same.

In Figures 5 and 6 of the drawing, I have shown a modification wherein the receptacle is substantially cylindrical in cross section and comprises the two semi-circular sections 90 18 and 19 respectively, the section 18 being adapted to rotate over the section 19 in the manner shown in the dotted lines in Figure 5 of the drawing when a music roll supported therein is to be played. The end 95 walls 20 are provided with the annular flanges 21 which provide a guide means for the movable section 18 in the manner as clearly shown in the drawing. It is also to be understood that the end walls of the 100 cylindrical receptacle are provided with opening such as is shown at 22 for the reception of the trunnions of the music roll in the well known manner.

It will thus be seen from the foregoing 110 description, that a music roll box has been provided which is very simple in construction, inexpensive, and will be easily and quickly opened or closed whenever desired.

While I have shown the preferred embodiment of my invention, it is to be understood that various changes in the size, shape and arrangement of parts may be resorted to without departing from the spirit of the invention and the scope of the appended 115 claims.

Having thus described the invention, what I claim is:—

1. In combination with a music roll, of a box therefor comprising a bottom, end walls 125 extending upwardly therefrom, an upstanding wall formed on the forward edge of the bottom, an upstanding wall formed on the rear edge of said bottom, said upstanding walls extending for the full length of the 130

bottom, a rear wall hinged at its lower edge to the rear upstanding wall, the upper edge of said rear wall extending substantially flush with the upper edges of the end walls, a top hinged to the upper edge of said rear wall and extending substantially flush with the forward edge of the bottom, a front wall hinged to the forward edge of said top, the lower portion of said front wall overlapping the upstanding wall on the forward edge of the bottom and adapted to be secured thereto.

2. In combination with a music roll, of a box therefor comprising a bottom section, 15 end walls extending upwardly therefrom, said end walls having inwardly extending flanges formed on the sides and top thereof, an upstanding wall formed on the forward longitudinal edge of said bottom section, an 20 upstanding wall formed on the rear longitudinal edge of said bottom, a rear wall hinged at its lower edge to the last mentioned upstanding wall, the upper edge of said rear wall extending flush with the upper edges of the end walls, a top hinged to the upper edge of said rear wall and extending flush with the forward edges of the end walls, a front wall hinged to the forward edge of the top and having the lower portion thereof arranged in overlapping arrangement with the upstanding wall formed on the forward edge of the bottom section, and fastening means therefor.

3. In combination with a music roll, of a box therefor comprising a bottom section, 35 end walls extending upwardly therefrom, said end walls having inwardly extending flanges formed on the sides and top thereof, an upstanding wall formed on the forward longitudinal edge of said bottom section, an upstanding wall formed on the rear longitudinal edge of said bottom, a rear wall hinged at its lower edge to the last mentioned upstanding wall, the upper edge of 40 said rear wall extending flush with the upper edges of the end walls, a top hinged to the upper edge of said rear wall and extending flush with the forward edges of the end walls, a front wall hinged to the forward edge of the top and having the lower portion thereof arranged in overlapping arrangement with the upstanding wall formed on the forward edge of the bottom section, fastening means therefor, the flanges of said end walls having openings provided therein to permit the insertion of the music roll with the box, said end walls having openings arranged centrally therein to receive the trunnions of the music roll.

In testimony whereof I affix my signature.

MYRTLE A. ANDES.
